United States Patent Office.

GEORGE H. BUCKIUS, OF CANTON, OHIO, ASSIGNOR TO HIMSELF, C. AULTMAN, A. C. TONNER, AND P. H. SOWERS, OF SAME PLACE.

Letters Patent No. 79,725, dated July 7, 1868.

IMPROVED HARNESS-RING.

The Schedule referred to in these Letters Patent and making part of the same.

TO ALL WHOM IT MAY CONCERN:

Be it known that I, GEORGE H. BUCKIUS, of Canton, in the county of Stark, and State of Ohio, have invented an Improved Harness-Ring; and I do hereby declare that the following is a full, clear, and exact description of my invention, reference being had to the accompanying drawings, forming a part of this specification, and to the letters of reference marked thereon, of which drawings—

Figure 1 is an elevation of my improved ring.

Figure 2 is a plan of the same.

Figures 3 and 4 are elevation and plan, showing the application of my improved ring.

The nature of my invention consists in the construction of a ring, with one or more arms on its periphery, said arms being of such form as to be sewed in between the rows of stitches at the sides of the leather to which the ring is attached, whereby any sliding of the leather around the ring is prevented; and where two or more straps are attached to the same ring, and an arm is used in combination with each strap, the straps are maintained in their relative positions with respect to each other and to the ring, which is very advantageous in many places in a harness, as well as in halters, and other articles of a similar class.

To enable others skilled in the art to make and use my invention, I will proceed to describe its construction and application.

The ring A is composed of malleable iron, or any other suitable material, and has arranged on its periphery the arms B, which are cast with the ring A, or attached to it in any other suitable manner.

These arms B are of an elongated flattened form, of any suitable length, and can be arranged on the ring A in any suitable manner.

When the ring is applied to use, as, for instance, at the connection of the nose-piece and head-pieces of a halter, the straps C are turned over the ring and one arm, as shown, and the whole is secured in position by the rows of stitches c c, at each side of the strap C, and on each side of the arm B, as shown.

Having thus fully described my invention, what I claim as new, and desire to secure by Letters Patent, is—
A ring, A, having one or more arms, B, arranged on its periphery, substantially as and for the purpose specified.

As evidence that I claim the foregoing, I have hereunto set my hand in the presence of two witnesses, this 7th day of May, A. D. 1868.
